Inventor,
William W. Crane

United States Patent Office.

WILLIAM W. CRANE, OF PHILADELPHIA, PENNSYLVANIA.

Letters Patent No. 82,294, dated September 22, 1868.

IMPROVEMENT IN DOORS FOR FURNACES.

The Schedule referred to in these Letters Patent and making part of the same.

TO ALL WHOM IT MAY CONCERN:

Be it known that I, WILLIAM W. CRANE, of the city of Philadelphia, and State of Pennsylvania, have invented a new and useful Ash-Pit Door for Furnaces, Heaters, &c.; and I do hereby declare that the following is a full, clear, and exact description of the same, reference being had to the accompanying sheet of drawings, and to the letters of reference marked thereon, making part of this specification, in which—

Figure 1 is a plan view, and

Figure 2 is a sectioned elevation.

Similar letters refer to similar parts in the two views.

My invention consists of an air-tight ash-pit door, which is so constructed, with reference to the flange or rib on the ash-door plate, as to have the means of regulating the quantity of air admitted to the fuel, the door having a valve or opening; and to this end I form a rim or elevation, A, on the door-plate B, which conforms completely with the inner surface of the rim, a, of the door C; the upper edge or top of the elevation A, taking against the under surface of the top of the door, and the bottom or edge of the rim a resting against the door-plate, thus accurately fitting on all three surfaces, thereby making a practically air-tight door. The door has a hole or opening, b, which is regulated by a slider, c, at which the necessary quantity of air is admitted to preserve combustion.

The door is operated like all furnace-doors; it turns on the pin D, which takes through its lugs, E E, and the jaws G G, of the door-plate B. When closed, the weight of it is in part taken from the jaws by the projection H, in the front of the door, taking on to the projection I, of the door-plate.

The door C and the flange A should be accurately cast, so as not to require fitting; the vitreous surface of the metal is thereby retained, and it is, of consequence, prevented from rusting, and the door kept air-tight.

What I claim as my invention, and desire to secure by Letters Patent, is—

The door-plate B, rim or elevation A, and the door C, when constructed and arranged substantially as and for the purpose shown and described.

In testimony whereof, I hereunto sign my name to this specification in presence of two subscribing witnesses.

WILLIAM W. CRANE.
